UNITED STATES PATENT OFFICE.

EDWARD A. KAHN AND RALPH A. SEIGLE, OF INDIANAPOLIS, INDIANA.

DISPLAY DEVICE.

No. 823,536.

Specification of Letters Patent

Patented June 19, 1906.

Application filed March 21, 1905. Serial No. 251,262.

To all whom it may concern.

Be it known that we, EDWARD A. KAHN and RALPH A. SEIGLE, citizens of the United States, residing at Indianapolis, in the county of Marion and State of Indiana, have invented a new and useful Display Device, of which the following is a specification.

This invention relates to devices for displaying fabrics of various kinds—such as carpets, 10 pets, mattings, hangings, curtain material, and the like—and which may also be employed for displaying samples of wall-paper and similar goods, and has for its object to provide a drum mounted for rotation and 15 having means for detachably connecting the samples of goods thereto in position to be independently displayed and also independently attached or detached to change the samples as required.

20 With these and other objects in view, which will appear as the nature of the invention is better understood, the same consists in certain novel features of construction, as hereinafter fully described and claimed.

25 In the accompanying drawings, forming a part of this specification, and in which corresponding parts are denoted by like designating characters, is illustrated the preferred form of embodiment of the invention capable 30 of carrying the same into practical operation.

In the drawings thus employed, Figure 1 is a longitudinal sectional elevation of the improved device. Fig. 2 is a transverse section enlarged.

35 The improved device comprises a drum 10 of any desired size and mounted upon a shaft 11, the latter supported for rotation in a frame 12 of any suitable form, and preferably with bearings 13, having rollers or balls 14 to reduce the friction. The surface of the drum 10 is provided with spaced longitudinal 40 grooves 15, substantially U-shaped in cross-section, and with end flanges 16 17, forming closures to the ends of the grooves and preferably of greater diameter than the drum. The flanges 16 17 are provided, respectively, 45 with spaced transverse slot-like apertures 18 19, elongated radially of the drum, with the bottoms of the apertures in alignment with the bottoms of the grooves in the drum and the tops stopping short of the tops of the grooves, each groove thus having slots at the ends leading through the flanges. Rods 20 are disposed in the channels 15 and extend 50 through the slots 18 19, each with a head 21

upon one end and a nut 22 upon the other end, bearing, respectively, against the outer faces of the end flanges 16 17, the said rods bearing against the bottom of the U-shaped groove, but being of smaller diameter than 60 the curve of the groove.

By this simple arrangement samples of fabrics of various kinds—such as carpets, mattings, curtain material, hangings, and the like, (indicated at 23)—may be quickly secured in position upon the drum by folding one end and inserting it into the channels or grooves 15 and then inserting the rod 20 through one of the slots 16 or 17 and within the fold of the fabric and thence through the other aperture and applying the binding-nut, the slotted form of the apertures permitting the rods to be compressed tightly against the portion of the fabric within the channels, and thus hold them in position when the nuts are applied. The slotted apertures thus permit the rods to be adjusted to fabrics of different thicknesses, as will be obvious.

If required, transversely-disposed staples 24 may be inserted at one or more points as 80 an additional holding means.

The drums may be of any required size either in diameter or length and may contain as many of the grooves as required and of any size to correspond to different kinds or 85 thicknesses of fabric or other goods.

The device may be inexpensively constructed and employed to advantage in wholesale or retail stores.

Having thus described the invention, what 90 is claimed is—

1. A display device comprising a rotatable drum provided with grooves in its periphery disposed longitudinally and substantially U-shaped in cross-section, rods disposed longitudinally within the grooves and means to secure the rods at varying distances from the bottoms of the grooves.

2. A display device comprising a rotatable drum provided with grooves in its periphery disposed longitudinally and substantially U-shaped in cross-section, flanges carried at the ends of the drum and provided with radial slots registering at their lower ends with the bottom of the grooves, rods inserted through 105 alined slots and disposed within the grooves and means of securing the rods at varying distances from the bottoms of the grooves.

3. A display device comprising a rotatable drum provided with grooves in its periphery 110

disposed longitudinally and substantially U-shaped in cross-section, flanges carried at the ends of and outstanding beyond the periphery of the drum and provided with radial slots registering at their lower ends with the bottom of the groove but the top stopping short of the top of the groove, rods disposed within the grooves and extending at each end through the slots and means carried upon the opposite ends of the rods and without the

flanges to secure the rods at varying distances from the bottoms of the grooves.

In testimony that we claim the foregoing as our own we have hereto affixed our signatures in the presence of two witnesses.

EDWARD A. KAHN.
RALPH A. SEIGLE.
